PICKING CAM AND MOUNTING THEREFOR

Benjamin W. Brouwer, Auburn, and Victor F. Sepavich, Worcester, Mass., assignors to Crompton & Knowles Loom Works, Worcester, Mass., a corporation of Massachusetts

Application May 29, 1947, Serial No. 751,206

8 Claims. (Cl. 139—147)

1

This invention relates to improvements in picking mechanisms for looms and it is the general object of the invention to provide an improved picking cam and mounting therefor for the purpose of making the cam operate more smoothly when force is applied thereto by an actuator.

The picking mechanism for some looms includes a rockable shaft carrying a picker cam the working surface of which lies in the path of a rotating actuator or picking roll. The shaft carries a picking arm which is connected by a sweep stick to the picker stick and rocking of the shaft causes the picker arm to operate the picker stick. As made heretofore the shafts have been so mounted that they bend somewhat at the beginning of the picking operation with the result that the first part of the movement of the picking roll along the cam is ineffective to move the picker stick.

It is an important object of the present invention to provide a picking cam so made that it can accommodate a bearing for the picking shaft and prevent bending of the shaft incident to engagement of the picking roll with the picking cam. The entire time during which the picking roll engages the cam is therefore available for acceleration of the shuttle.

In the type of picking mechanism already mentioned it is frequently a difficult matter to replace a broken or worn picking cam due to the manner in which the picking shaft is mounted in its bearings. It is another object of the present invention to provide a picking cam including a sleeve which can be readily removed to permit easy replacement without removing the picking shaft from the loom.

It is a further object of the invention to provide a picking cam so formed that it can accommodate a picking shaft bearing between its ends.

With these and other objects in view which will appear as the description proceeds, our invention resides in the combination and arrangement of parts hereinafter described and set forth.

In the accompanying drawings, wherein a convenient embodiment of our invention is set forth,

Fig. 1 is a side elevation partly in section of a loom having the invention applied thereto.

Fig. 2 is an enlarged vertical section on line 2—2 of Fig. 1.

Fig. 3 is a horizontal section on line 3—3 of Fig. 2, and

Figs. 4 and 5 are reduced vertical sections on lines 4—4 and 5—5, respectively, of Fig. 3.

Referring particularly to Fig. 1, the loom frame 10 supports top and bottom shafts 11 and 12, re-

spectively, which are connected by the usual gears 13 and 14. A lay 15 is reciprocated backwardly and forwardly by means of connectors one of which is shown at 16. A shuttle S is picked back and forth across the lay by picker sticks one of which is shown at 17. Each picker stick is connected by a sweep stick 18 to a picker arm 19 mounted on the corresponding picker shaft 20 which extends backwardly and forwardly in the loom. Each shaft 20 is preferably of rectangular cross-section and may have front and back bearings 21 and 22, although as will appear hereinafter we are not necessarily limited to the kind of bearings for the picking shaft shown in Fig. 1. Bottom shaft 12 is usually provided with two oppositely extending actuator or sweep arms, but herein we show only one pump arm at 23 in Fig. 1 having rotatably mounted thereon a picking roll or ball 24. The roll moves in a vertical path and completes a revolution every second pick of the loom. In the usual type of loom the picking rolls are alternately operative to pick the shuttle.

The matter thus far described is of common construction, but we do not wish to be limited to the bearings of the picking shaft or the particular position shown for the bottom shaft 12.

In carrying our present invention into effect we provide an improved picking cam designated generally at C and an auxiliary bearing B for the picker shaft 20. Both sides of the loom are equipped with a cam C and bearing B, but the following description will be limited to one side only of the loom.

The bearing B has a foot 30 provided with horizontal slots 31 which receive bolts 32 by means of which the bearing is securely fastened to the loom frame. The slots permit a limited amount of horizontal adjustment of the bearing B in the direction of the length of shaft 20. The bearing has a hub 33 within which is rotatably mounted a bushing 34 having a rectangular hole 35 therethrough to fit the shaft 20.

As shown more particularly in Fig. 3 cam C comprises three parts which are the cam shoe 49 and two end plates or collars 41 and 42. The shoe is provided with the cam surface 43 which engages the picking roll 24 and extends along a vertical wall 45 provided with a shelf or rib 46 formed as shown for instance in Figs. 2 and 5. The wall and rib are substantially parallel to the shaft 20.

The end plates 41 and 42 are alike and are located on opposite sides of the hub 33. Each end plate has a square hole 47 therethrough which fits the shaft 20, and screws 48 and 49

pass through the wall 45 and into the end plates 41 and 42, respectively, to hold the shoe firmly in position on the end plates. Each end plate has a notch 50 which receives the adjacent part of the angular rib 46. The latter is held tightly in the notches 50 of the two end plates by the bolts 48 and 49. Set screws 51 hold the end plates on shaft 20 with the plates spaced slightly from the bearing and bushing.

In operation, the roll 24 will move in the direction of arrow *a*, Fig. 1, and after engaging the low side 52 of the cam will ride therealong to the high side 53, thereby depressing the cam and rocking shaft 20. Because of the fact that hub 33 is located as indicated in Fig. 3 there will be no appreciable downward deflection of that part of the shaft 20 on which the cam C is mounted and as a result picking arm 19 will move continuously and at the desired accelerated rate to impart correct movement to the shuttle from the time the roll 24 first engages the low point 52 of the cam until it leaves the high point.

In previous picking motions of this general type the cam has been between the bearings for the shaft 20 with the result that upon initial engagement of the roll 24 with the low point 52 the shaft 20 has deflected downwardly and the first part of the movement of the roll 24 has been lost so far as effective movement of the shuttle is concerned. By having the bearing B related to the cam substantially as shown for instance in Figs. 1 and 3 angular movement of the shaft 20 is continuous throughout engagement of the cam with the picking roll.

Continued use is likely to produce wear on the cam 43 necessitating replacement thereof. Under these conditions the bolts or screws 48 and 49 are removed, after which the wall 45 is lifted until rib 46 clears notches 50, whereupon the shoe can be entirely removed from the end plates. By a reverse process a new shoe is attached to the end plates and the cam is ready for use. This operation does not require removal of shaft 20 from bearing 33, nor is it necessary to loosen the end plates. If the bushing becomes worn, one of the end plates is removed to permit endwise sliding of the bushing out of bearing 33.

While we have shown the end plates 41 and 42 as being separate from the shoe 40 it is within the spirit of certain features of the invention to make these three parts in one piece which they in effect are when the screws 48 and 49 are tight. In any event, the cam 43 or shoe 40 has parts rigid therewith which lie on opposite sides of a bearing for the picker shaft.

From the foregoing it will be seen that we have provided simple means by which the picking cam can be made to accommodate a bearing for the picking shaft. The bearing is preferably within the limits of the picking cam, or at least between its ends measured in the direction endwise of the shaft 20. As a result of this construction the shaft 20 is held against downward deflection at the beginning of a picking stroke and the whole period of engagement of the picking roll 24 with the cam 40 is effective for rocking the shaft 20.

It will also be seen that when the end plates 41 and 42 are made more particularly as set forth herein they permit removal of the shoe 40 for replacement purposes without disturbing the bearing 33 or the shaft 20.

Having thus described our invention it will be seen that changes and modifications may be made therein by those skilled in the art without departing from the spirit and scope of the invention and we do not wish to be limited to the details herein disclosed, but what we claim is:

1. In a loom provided with a picking shaft, a picking cam on said shaft comprising a cam shoe and spaced end plates rigid with respect thereto secured to the shaft, and a bearing for the shaft between said end plates and secured to the loom.
2. In a loom provided with a picking shaft, a picking cam on said shaft comprising spaced end plates secured to the shaft and a picking shoe secured to the plates, and a bearing for the shaft between said plates and secured to the loom.
3. In a loom provided with a picking shaft, a picking cam on said shaft comprising spaced end plates secured to the shaft and interlocked with a picking shoe secured thereto, and a bearing for the shaft between said plates and secured to the loom.
4. In a loom provided with a picking shaft, a picking cam on said shaft comprising spaced end plates secured to the shaft, a picking shoe, removable means securing the shoe to said plates, and a bearing for the shaft between said end plates and secured to the loom.
5. In a loom provided with a picking shaft, a picking cam on said shaft comprising spaced end plates, removable means normally holding said plates secured to the shaft, a bearing for the shaft between said plates and secured to the loom, and a picking shoe secured to said end plates.
6. In a loom provided with a picking shaft of non-circular cross section, end plates spaced from each other longitudinally of the shaft, removable means normally securing said plates to the shaft, a bushing surrounding said shaft between the plates, a bearing between the plates for the bushing mounted on the loom, and a picking shoe secured to said end plates.
7. In a loom provided with a picking shaft of non-circular cross section, end plates spaced longitudinally on the shaft and having non-circular holes fitting the shaft and secured to the latter, a picking shoe secured to the end plates, a bushing between the plates having a hole of non-circular cross section therethrough fitting the shaft, and a bearing for the bushing between the plates and secured to the loom.
8. In a loom provided with a picking shaft, a picking cam on said shaft comprising a cam shoe having a rib thereon extending longitudinally of the shaft, spaced end plates secured to the shaft and having aligned notches receiving said rib, removable means securing the shoe to the end plates, and a bearing for the shaft between said end plates and secured to the loom.
